LOOP PICKER

Clarence M. Fuller, Warwick, R. I., assignor to
Holbrook Raw Hide Co., Providence, R. I., a corporation of Rhode Island

Application October 9, 1947, Serial No. 778,875

9 Claims. (Cl. 139—159)

1

This invention relates to a novel and improved construction of loop-picker for use in textile looms.

One object of the invention is to provide a loop-picker of strong and rugged construction adapted to cushion the shock from the impact of the shuttle and prevent damage to the picker-stick while minimizing wear and providing maximum durability for long periods of use.

Another object is to provide a loop-picker constructed from several different materials arranged in a novel and ingenious manner to prevent splitting, spreading and bulging at its sides liable to cause wear on or damage to the shuttle-box in the loom.

Another object is to provide a novel construction of loop-picker having a continuous strap looped around a hard block and riveted thereto to prevent it from becoming loose to allow the picker to twist or be otherwise displaced from proper position on the picker-stick.

Another object is to provide an improved loop-picker having the ends of the rivets protected to prevent them from abrading the sides of the shuttle-box in the loom and also secured against becoming loose and falling out to damage other parts of the loom.

Another object is to provide an improved construction of loop-picker having its contact end protected by a hollow cap enclosing the body or core of the picker to prevent the latter from spreading or bulging to chafe the sides of the shuttle-box or to jam therein.

Another object is to provide an improved construction of loop-picker having a relatively hard, substantially solid block arranged to bear against the face of the picker-stick flush therewith to prevent the picker from twisting thereon or from wearing into the grain of the wood.

Another object is to provide an improved loop-picker that may be used at either end of the loom to overcome the disadvantages of requiring separate right- and left-hand units.

Further objects of the improvement are set forth in the following specification which describes several preferred forms of construction of my improved loop-picker as illustrated by the accompanying drawings. In the drawings:

Fig. 1 is a side elevational view of one form of the improved picker;

Fig. 2 is a longitudinal sectional view of the same taken in a median vertical plane;

Fig. 3 is a top plan view of the picker;

Fig. 4 is a sectional plan view of the same taken on line 4—4 of Fig. 1;

2

Fig. 5 is a transverse sectional view through the core of the picker taken on line 5—5 of Fig. 1;

Fig. 6 is a view similar to Fig. 1 illustrating a modified form of construction of the picker showing it enclosed by a metal sheath;

Fig. 7 is a longitudinal sectional view of the picker shown in Fig. 6 taken in a median vertical plane;

Fig. 8 is a top plan view of the picker shown in Fig. 6;

Fig. 9 is a transverse sectional view of the same taken on line 9—9 of Fig. 6;

Fig. 10 is an elevational view of the forward end of the picker shown in Fig. 6; and

Fig. 11 is a rearward end view of the same.

Heretofore it has been the usual practice to construct loop-pickers from leather or laminations of textile fabric bonded together with rubber compound. Leather pickers are liable to split or spread causing them to expand or swell laterally to bind in the shuttle-box and cause damage thereto, sometimes jamming therein and throwing the shuttle out of the loom. Such pickers also have the disadvantage of twisting on the picker-stick due to their backing being too soft to hold them in rigid connection therewith.

Rubber pickers have the same faults mentioned above and are also affected by heat generated by suction developed as the shuttle-nose enters the picker; the heat rendering them soft and flexible and thus subject to rapid deterioration.

The usual metal rivets in leather and fabric pickers are liable to become loose, due to the softness of the picker material, so that their ends project at the sides to abrade and damage the sides of the shuttle-box and frequently the rivets become loose and drop out to damage other parts of the loom. Leather and fabric pickers must be made right- and left-hand due to the fact that the lap in the loop is on the weaker outward side and therefore must be properly related to the shuttle-box.

In some instances loop-pickers have been constructed from all rawhide or a combination of rawhide and fabric, but in such constructions the core is so hard that it cannot cushion the impact or blow of the shuttle, thereby causing gouging of the picker-stick so that the picker becomes loose and cannot function efficiently.

To overcome the above and other defects and deficiencies in previously-used picker constructions I have provided a novel and ingenious form of loop-picker having its body or core composed of laminations of several different materials arranged in abutting relation to a substantially

solid block for engaging the face of the picker-stick with the head or core of the picker protected from spreading or expanding by being enclosed on all sides by a hollow cap of relatively hard material.

In the form of construction shown in Figs. 1 to 5 of the present drawings a hard, rigid block 2, preferably composed of laminations comprising relatively thick strips 3 of hard rawhide, is adapted to abut the forward face of the picker-stick (not herein shown) to prevent the picker from twisting or turning on the stick. The picker is connected to the stick by means of a loop 5 which may be made of a continuous length of leather to prevent it from being pulled apart or separated. The loop 5 is looped around the block 2 and fastened to its side by means of two steel pins 6, 6 having their ends riveted through the sides of the cap 7 which encloses the core of the picker.

The cap 7 is constructed of hard rawhide moulded in hollow box-like form under compression to further strengthen and solidify the material. The cap 7 entirely surrounds all four sides of the core of the picker and is held and reinforced by the rivets 6 to prevent any lateral expansion of the core. Preferably, the sides of the cap 7 are recessed at 8 and 9, see Figs. 1, 4 and 5, to form outwardly-projecting ribs 10 at top and bottom of the sides and a further rib 11 between the two rivets 6. In this way the heads of the rivets 6 are recessed inwardly between the ribs and protected thereby to prevent their ends from rubbing against the sides of the shuttle-box to insure against damaging the latter. Moreover, the rivets 6 being forced through the hard solid block 2 are effectually secured against becoming loose under shock or jar to cause their ends to project beyond the sides of the picker and damage the sides of the shuttle-box.

Between the end of the cap 7 and the side of the stick-contact block 2 are a plurality of inserts, comprising a combination of different materials, each designed for a particular purpose. Abutting the inner face of the end of the cap 7 is a strip 12 of hard rawhide, this insert cooperating with the end of the cap to take the wear of the steel-shod point of the shuttle. The next or second insert 13 may be of softer rawhide or leather to provide more of a cushion, and the third insert 14 is preferably hard rawhide again for wear resistance. It is to be particularly noted that these inserts or laminae 12, 13 and 14 extend laterally across the picker or, in other words, they are disposed at right-angles or perpendicularly to the axis of the shuttle. The three inserts 12, 13 and 14 are rather loosely held within the cap 7 to provide a full floating arrangement so that they may contract under the impact from the blow of the shuttle as it strikes the picker, and then expand again with a cushioning effect. As will be observed by reference to Fig. 4 of the drawings the third or inner insert 14 abuts the inner end of the loop 5 which surrounds the block 2 and between this end of the loop and the block 2 I preferably provide a strip of resilient material 15 such as soft rubber to act as a cushion or shock-absorber for relieving the blow of the block against the stick. Referring to Figs. 1 to 3 of the drawings, the contact end of the picker is provided with the usual conical recess or socket 16 for receiving the metal-shod end of the shuttle and the angle or flare of this recess is preferably greater than the taper of the nose of the shuttle to provide

that the terminal point of the nose will engage against the last hard rawhide insert 14 to take the impact. Consequently, the steel shoe or nose of the shuttle will not have a tendency to compress and spread the material of the inserts to any great extent. Furthermore, there will be less tendency to generate heat due to suction.

As before noted all the several inserts 12, 13, 14 and 15, as well as the end of the leather loop 5 are disposed crosswise or transversely in lateral relationship in the core of the picker as distinguished from the usual arrangement in which the inserts or laminations extend longitudinally of the picker. In previous constructions, therefore, as the point of the shuttle enters the end of the picker it has a tendency to separate and spread the laminations thus causing the body of the picker to expand laterally and thereby unfit it for efficient operation after it has been in use for a short period of time. With my present improved construction the blow of the shuttle is taken at right-angles or perpendicularly to the direction of its impact, that is on the face instead of the edges of the inserts, and consequently there is no tendency to spread or split the core to cause the picker to expand or bulge at its sides.

Referring now to Figs. 6 to 11 of the present drawings, a modified form of the picker is therein illustrated involving further improvement as next explained. In general, the core of the picker shown in Figs. 6 to 11 is similar to that illustrated in Figs. 1 to 5. The body or core of the picker may comprise a solid stick-contact block 20 enclosed within the rearward end of the hard rawhide cap 21 and fastened in place by two rivets 22 headed over at their ends. The loop 23 is constituted as a continuous leather strap encircling the block 20 and held to its sides by the rivets 22 as previously described. Between the looped end of the strap 23 and the block 20 is a strip 24 of rubber, relatively soft leather or other resilient material and between the end of the cap 21 and the end of the loop are three laminae similar to those previously described in connection with Figs. 1 to 5. The first strip 25 is constructed of exceedingly hard rawhide, the next strip 26 is of softer rawhide or, in other cases leather, and the third strip 27 is of hard rawhide again. The several inserts 25, 26 and 27 are mounted within the cap 21 in relatively loose arrangement, that is not under compression, so that they may expand and contract more or less under the impact of the shuttle. As is the usual arrangement a tapering or conical socket 28 is provided at the end of the picker for receiving the steel point of the shuttle and the loop 23 may be punched with a hole 29 for receiving a screw or nail to fasten the picker to the stick.

As an added feature of improvement in the last described construction the picker is encased in a relatively thin metal shell or sheath 30. The sheath 30 is preferably constructed of sheet aluminum or similar metal for the sake of strength and lightness in weight and a metal blank may be shaped in dies to form an oblong box conforming to the shape of the picker itself. That is to say, the sheath or casing 30 may be constructed from a single strip of sheet-metal drawn up to provide continuous sides, except for openings 31 and 32 at the top and bottom which provide for the insertion of the picker-stick therethrough. Stated more specifically, the sheath or casing 30 is of hollow box-like form with its top and bottom walls cut away for the openings 31

and 32 on opposite sides of the loop 23; having a continuous end wall 33; continuous side walls 34, swelled outwardly at the fore part to enclose the cap 21; and relatively narrow marginal portions of the metal 35 and 36 folded inwardly at the forward corners of the cap and meeting in mortised joints which may be soldered or welded as desired. The rectangular opening 31 in the bottom wall of the sheath 30, see Fig. 7, and the opening 32 in the upper or top wall are slightly larger than the opening between the sides of the loop 23 and the side of the block 20. That is to say, the portions of the top and bottom walls of the sheath or casing 30 which form the overlying marginal strips surrounding the opening through the loop 23 are relatively narrow so that their edges will not project beyond the edges of the leather strap. The purpose of this offsetting of the edges of the metal around the openings 31 and 32 is to insure against any chance that the sharp edges of the metal might cut into the sides of the stick.

It will be observed from the foregoing specification that the present invention provides an especially strong, rugged and durable picker having many advantages as now set forth. First, my improved construction of the picker permits it to be manufactured in one form only to render it capable of interchangeable use at either end of the loom. Secondly, the strap or loop for holding the picker on the stick is continuous to prevent it pulling away or loosening and thereby allowing the picker to twist or sag on the stick and prevent its proper operative relation to the shuttle. As another advantage, the hard solid block which abuts the face of the stick provides a firm bearing thereon to prevent twisting or rocking of the picker and further insure its proper positioning with respect to the shuttle. The hard continuous cap which completely encloses the body or core of the picker augments its strength and extends its durability by preventing expansion or swelling of the core. The recessing of the ends of the rivets as shown in the first form of construction, Figs. 1 to 5, or the covering of their ends by the metal sheath or shell, prevents scoring or abrading the sides of the shuttle-box when the picker is in use in the loom.

The full floating arrangement of the laterally-extending inserts at the front or working end of the picker is of paramount advantage: the rawhide inserts provide a hard, wear-resisting contact surface for the metal shoe of the shuttle; the softer rawhide or leather insert furnishes a resilient cushion to take the shock of the shuttle impact, and this cushioning effect is further augmented by the rubber insert abutting the forward face of the stick-contact block. In this way, the picker-stick is relieved of the shock and saved from wear and splintering or gouging of the wood, and as a further advantage the shock is absorbed to prevent the shuttle from rebounding from the picker. In other types of pickers where the contact end is of leather, or fabric impregnated with rubber, the shuttle is prone to rebound from the picker and consequently when the picker is actuated to throw the shuttle it will strike the latter with a sharp blow and cause greater wear on the parts. By thus preventing rebound of the shuttle the springs in the shuttle-box can be adjusted to relatively light contact therewith to reduce the wear on its sides. It is believed that these and other advantages of the present construction make for a very considerable improvement in loop-pickers of this type, par-

ticularly for use in high-speed looms now in wide use for increasing production.

The metal sheath encasing all parts of the picker, including its loop, has several advantages.

5. First, it reinforces the whole structure against splitting, spreading or rupturing and further it prevents the fibers of the rawhide and leather from ruffing up and catching lint or bits of yarn in the loom, presenting a smooth polished surface to reduce the friction between the picker and other parts of the loom.

While the improvement is herein described and illustrated as embodied in two preferred forms of construction, it is to be understood that further modifications may be made in the structure and arrangement of the parts of the device without departing from the spirit or scope of the invention. Therefore, without limiting myself in this respect, I claim:

20. 1. A loop-picker comprising a multi-part core consisting in a hard block of animal hide shaped to contact the face of a picker-stick, a loop fastened to said block and extending rearwardly therefrom to attach it to the picker-stick, a plurality of inserts consisting in strips of alternate hard and soft material extending transversely of the core forwardly of the block, and a box-like cap of animal hide enclosing the front and four sides of the core with the inserts contained therein in full floating arrangement.

25. 2. A loop-picker comprising a multi-section core consisting in a hard block of rawhide, a continuous loop extending around the core and riveted to its sides, an insert of resilient material between the end of the loop and the rawhide block, a box-like cap enclosing the front and four sides of the core, and a plurality of inserts of alternate hard and soft material disposed transversely of the core in free floating arrangement between the end of the cap and the end of the loop.

30. 3. A loop-picker constructed with a composite core comprising a hard block of rawhide adapted to contact the face of a picker-stick, a continuous loop extending around the core and projecting therebeyond for attachment to a picker-stick, a hard rawhide box-like cap surrounding the front and four sides of the core, pins inserted through the sides of the cap, the sides of the loop and frictionally held in the contact-block, and a plurality of strip-like inserts of alternately hard and soft rawhide extending laterally across the core in laminated full floating arrangement between the end of the cap and the inner end of the loop.

35. 4. A loop-picker constructed with a laminated core comprising a block composed of strips of hard rawhide, said core adapted to contact the face of a picker-stick, a loop consisting in a leather strap looped around the block and extending rearwardly therefrom for holding the picker to the stick, an insert of resilient material between the forward end of the loop and the forward face of the block, a box-like cap of hard rawhide enclosing the front and four sides of the core, rivets connecting the cap to the loop and block, and a plurality of inserts of alternate hard and soft rawhide held in free-floating relationship within the cap between its end and the end of the loop.

40. 5. A loop-picker constructed with a composite core comprising a hard block of animal hide shaped to contact the face of a picker-stick, a strap looped around the block and extending rearwardly therefrom for engagement around a picker-stick, a cap enclosing the end and sides

of the core with a plurality of inserts extending transversely within its interior between its ends and the end of the loop, said cap formed with projecting ribs on its sides, and pins inserted through the sides of the cap, the sides of the strap and the block with their ends headed over within recesses between the ribs on the sides of the cap.

6. A loop-picker constructed with a composite core comprising a rectangular block of hard rawhide shaped to contact the face of a picker-stick, a strap looped around the block and extending rearwardly therefrom for attaching the picker to the stick, an insert of rubber between the inner end of the strap and the block, a box-like cap enclosing one end and the sides of the core, rivets extending through the sides of the cap, the sides of the strap and the block, and a plurality of inserts held in floating arrangement within the forward part of the box between its closed end and the end of the strap, two of said inserts being of hard rawhide separated by a third insert of softer material.

7. A loop-picker constructed with a composite core comprising a hard block of animal hide shaped to contact the forward face of a picker-stick, a flexible strap looped around the block, a cap of hard animal hide enclosing one end and the sides of the core, pins extending through the core and strap and riveted through the sides of the cap, a plurality of inserts of alternate hard and soft material held in floating arrangement between the end of the cap and the end of the strap, and a metal casing enclosing the core and the loop on all sides with openings at top and bottom for insertion of the stick therethrough.

8. A loop-picker constructed with a composite core comprising a hard block of animal hide shaped to contact the forward face of a picker-

stick, a flexible strap looped around the block, a cap of hard rawhide enclosing one end and the sides of the core, pins extending through the core and riveted through the sides of the cap, a plurality of inserts of alternate hard and soft material held in floating arrangement between the end of the cap and the end of the strap, and a metal casing enclosing the core and the loop on all sides with openings at top and bottom for insertion of the stick therethrough, said casing having portions folded over the corners at the front of the cap to permanently secure it in place on the picker.

9. A loop-picker comprising a multi-part core consisting in a hard block of animal hide shaped to contact the face of a picker-stick, a loop fastened to said block and extending rearwardly therefrom to attach the picker to the picker-stick, a plurality of inserts consisting in sections of alternately hard and soft material overlying the forward end of the block transversely thereof, and means for retaining said inserts in place at the forward end of the block.
